UNITED STATES PATENT OFFICE.

EMMETT E. EDEBURN, OF SHARON, PENNSYLVANIA.

WEATHER SEAL.

Application filed February 18, 1929. Serial No. 341,015.

This invention relates to the broad class of weather stripping structures and has more particular reference to an organization of structures cooperating in forming 5 what may be unitarily designated as a weather seal.

Stated more precisely, the invention has reference to a weather shield which is adapted especially for use on swinging doors, 10 the arrangement being such that the complete device is carried by the bottom of the door to provide a weather tight closure between the door and the floor and to avoid the necessity of using the common thresh- 15 old.

In carrying out the invention, I have evolved and produced a novel composite structure, wherein the parts are associated to provide a device which is exceptionally 20 efficient in performance, positive and dependable in action, smooth and quiet in operation, and capable of fulfilling the requirements of an invention of this class, in a satisfactory manner.

25 Other features and advantages of the invention will become more readily apparent from the following description and drawings.

In the drawings:

30 Figure 1 is a fragmentary elevational view of the door and door frame showing the weather shield or closure positioned on the door.

35 Figure 2 is a fragmentary view of the complete assembly, the hinged shutter being closed.

Figure 3 is a similar view to Figure 2, showing the shutter open.

40 Figure 4 is an end view of Figure 2 with the shutter closed.

Figure 5 is an end view with the shutter open.

Figure 6 is a face view of the door jamb or frame, showing a trip device.

45 Figure 7 is a perspective view of one end of the hinged rod showing the cam actuator carried thereby.

In the drawings, the reference character 8 designates door frames and 9 designates 50 the swingably mounted door.

In accordance with the present invention, the door frame has a recess formed therein, and an attaching plate set into this recess in flush relationship as shown in dotted lines in Figure 2. This carries a trip 10 having

an inclined nose functioning as an actuating cam.

The improved seal is formed principally of four distinguishable parts. The reference character 11 designates the right angularly shaped plate having the horizontal flange 12 arranged for attachment to the bottom edge of the door, and having its front or vertical flange depending, and connected to the last named flange is a reinforcing and joint closing plate 13. A similar right angularly shaped member 14 is provided and the horizontal flange 15 is interposed between the flange 12 and the bottom of the door. The vertical flange 16 is 70 merely for finishing the appearance of the structure.

The reference character 17 designates what may be generally termed a shutter. This comprises a vertical flange portion 18, 75 hingely connected as at 19, (see Figure 5) to the vertical flange of the member 11. The shutter also includes a laterally offset lip 20, carrying on its edge a suitable resilient strip which engages the floor 21 as 80 shown in Figure 4, when it is swung down to closed position. Embodied in the hinge structure is a pintle rod 22, (see Figure 7) having its opposite end portions bent laterally or at right angles as at 23, and a substantially U-shaped portion 24. This provides an abutment for cooperation with the cam trip 10. Incidentally, the opposite end of the plates 11 and 13 are notched to accommodate the nose of the cam 10, when the 90 door swings to a closed position.

The reference characters 25 and 26 designate brackets fastened to the right angularly shaped member 11 and shutter 17 respectively. The coil spring is interposed between and anchored at its opposite end upon the brackets, the spring being indicated by the reference character 27. It is of such tension as to automatically lift the shutter to the position seen in Figure 5. It follows 100 that when the door is opened, the shutter is in the raised or opened position seen in Figure 5. When however, the door is swung to closed position, it is obvious that the cam 10 on the door frame comes into play and 105 engages the U-shaped abutment 24 and thereby acts upon the hinged pintle and the bent end 23, to bring the shutter down to closed position seen in Figure 4. Thus when the door is closed, the weather seal is effec- 110

tive and closed. When the door swings open, however, the shutter swings up clear of the surface of the floor, so as not to interfere with freedom of motion of the door in 5 case of irregularity or improper hanging of the door.

This device is substantially automatic in 10 operation and eliminates the necessity of laying a threshold. It functions primarily as a weather strip or seal and cuts off draft. It eliminates plugging, drilling, and the use of nails or screws in cement, mosaic, and tile flooring, and prevents swelling or sticking of doors in wet or damp weather. 15 It may be used either inside or outside, is noiseless, has no contacting parts, such as would be subject to great wear, and it is quite inexpensive in installation and upkeep.

These and other advantages and features 20 of the invention have doubtless been made apparent from the foregoing description and drawings. Therefore, a more lengthy description is regarded as unnecessary.

Minor changes in the shape, size, and 25 arrangement of details coming within the field of invention claimed, may be resorted to, in actual practice, if desired.

I claim:

1. In a structure of the class described, 30 a door, a substantially right angularly shaped member having its horizontal flange attached to the bottom edge of the door, and having its vertical flange depending below the door, a shutter hingedly connected with 35 the lower edge of said depending flange, said shutter comprising a vertical attaching portion, and a laterally offset lip portion for engaging the floor.

2. In a structure of the class described, 40 a door, a substantially right angularly shaped member having its horizontal flange attached to the bottom edge of the door, and having its vertical flange depending below the door, a shutter hingedly connected with 45 the lower edge of said depending flange, said shutter comprising a vertical attaching portion, and a laterally offset lip portion for engaging the floor, springs connected at one end to the L-shaped member and at 50 the opposite end with the shutter, said spring being tensioned to automatically lift or swing said shutter to raised position.

3. In a structure of the class described, 55 a door, a substantially right angularly shaped member having its horizontal flange attached to the bottom edge of the door, and having its vertical flange depending below the door, a shutter hingedly connected with the lower edge of said depending 60 flange, said shutter comprising a vertical attaching portion, and a laterally offset lip portion for engaging the floor, springs connected at one end to the L-shaped member

and at the opposite end with the shutter, 65 said spring being tensioned to automatically lift or swing said shutter to raised position, and a relatively stationary trip pan cooperable with the shutter and adapted to swing the shutter downwardly to closing position when the door is in closed 70 position.

4. In a structure of the class described, in combination, a door, a substantially right angular attaching member fastened to the bottom of the door, a shutter fastened to the depending flange of said attaching member, the hinged means embodying a pintle rod having an extending end portion bent at right angles to engage the shutter and also including a U-shaped abutment, a relatively stationary cam cooperable with said abutment to swing the shutter down to closing position when the door is in closed 75 position.

5. In a structure of the class described, in combination, a door, a substantially right angular attaching member fastened to the bottom of the door, a shutter fastened to the depending flange of said attaching member, the hinged means embodying a pintle rod having an extending end portion bent at right angles to engage the shutter and also including a U-shaped abutment, a relatively stationary cam cooperable with said abutment to swing the shutter down to closing position when the door is in closed 80 position. 85

6. In a structure of the class described, in combination, a door, a substantially right angular attaching member fastened to the bottom of the door, a shutter fastened to the depending flange of said attaching member, the hinged means embodying a pintle rod having an extending end portion bent at right angles to engage the shutter and also including a U-shaped abutment, a relatively stationary cam cooperable with said abutment to swing the shutter down to closing position when the door is in closed 90 position, and spring means anchored at one end to the attaching member and at the opposite end to the shutter, said spring means actuating the shutter to raised open 95 position.

6. In a structure of the class described, in combination, a door, a substantially right angular attaching member fastened to the bottom of the door, a shutter fastened to the depending flange of said attaching member, the hinged means embodying a pintle rod having an extending end portion bent at right angles to engage the shutter and also including a U-shaped abutment, a relatively stationary cam cooperable with said abutment to swing the shutter down to closing position when the door is in closed position, and spring means anchored at one end to the attaching member and at the opposite 100 end to the shutter, said spring means actuating the shutter to raised open position, together with a joint sealing plate fastened to the door and bridging the gap existing between the door and said attaching member, and having its lower end depending beyond the hinged joint between the said attaching member and shutter. 105

In testimony whereof I affix my signature.

EMMETT E. EDEBURN.
